UNITED STATES PATENT OFFICE.

ARMIN TENNER, OF BERLIN, GERMANY.

CARTRIDGE-LOADING MACHINE.

SPECIFICATION forming part of Letters Patent No. 494,905, dated April 4, 1893.

Application filed May 26, 1892. Serial No. 434,476. (No model.)

To all whom it may concern:

Be it known that I, ARMIN TENNER, engineer, a citizen of the United States of America, residing at 13^a Grossbeerenste, Berlin, in the German Empire, have invented new and useful Improved Cartridge-Loading Machines, of which the following is a specification.

The subject matter of the present invention is a cartridge loading machine having a step like movement of the rotary table with its clamping bearings in which the cartridge cases are held and are successively brought beneath the tools or loading devices so that by each simultaneous operation of the same a cartridge is completely loaded. A device is combined with the rotary table consisting essentially of radially movable slides in order to bring felt wads cut out by hand or machine over the mouths of the cartridge cases at the moment when the same come beneath the punch immediately following the powder charging device. The same device can also be used for loading ball cartridges.

The invention also includes gearing for the rotary table: a reamer in connection with the powder charging device; a shot measure a device for upsetting the edge of the cartridge case and the well known devices for cutting, stamping and inserting the upper wad.

Figure 1 is a side view of the cartridge loading machine for shotcartridges. Fig. 2 is a vertical section; Fig. 3 a top view partly in section. Fig. 4 is a part horizontal section showing the clamps for the cartridge cases in top view. Fig. 5 is an elevation of the tool carrier in its lowest position, five cartridges being shown in section to demonstrate the operation of the parts. Fig. 6 is a section of the last tool for upsetting or turning down the edge of the cartridge case, on an enlarged scale. Fig. 7 is the section of a modification of the short charger. Figs. 8 and 9 represent in vertical section and top view a modification of the parts shown in Figs. 2 and 3 when the cartridges are to be loaded with bullets.

The frame of the machine consists of a base plate A and two standards B B' connected by a yoke C, the tool carrier D being guided in prismatic or other guide ways in the arms of the same. To the front of and beneath the tool carrier D, which moves vertically, is a feed wheel or rotary table E in the center of

which is the fixed standard A' which carries a stationary plate A². Between the standard A' and the conically bored nave E' of the rotary table E is an exteriorly conical annular member F which can be so adjusted by means of screws p q that a considerable friction can be produced on the surface of the nave in order to prevent all independent rotation of the table E under the impulse of the ratchet and pawl driving device. The movement of this device is in common with the stroke of the tool carrier D, derived from the horizontal shaft G which is driven by appropriate straps or in other suitable manner. The eccentric a with eccentric rod b which is in connection with the slide d with spring pawl c serve to transmit the movement of the shaft G so that the ratchet wheel e connected to the nave E' of the rotary table E receives its intermittent movement during each semi-rotation of the shaft G. The tool carrier D is reciprocated in vertical plane by the same being connected by the rod H to the crank I of the shaft G (Fig. 2).

The circumference of the rotary table E or the edge of the upper plate of the same and the annular part E² beneath the same is, as will be seen from Figs. 2 and 3 so recessed to form the part of a cartridge bearing i, that the cartridge cases can be inserted from the exterior to be transported under the various tools during the rotation of the table E.

The number of recesses i correspond with the number of teeth in the ratchet wheel e each recess corresponding with a clamping lever j moving around the fulcrum j' within the rotary table E and operated by means of a suitable spring f.

The flange U arranged at appropriate height above the base plate and running almost entirely around the same serves to support the transported cartridge cases so that the same cannot fall out until they reach the open space Z where as is shown in Fig. 4 the flange is interrupted so as to allow the finished cartridge to fall out of the machine. The clamping levers j are held open for a part of their travel and the action of their springs overcome by the shorter arms of the same, which carry antifriction rollers j', coming into contact with an extension u' of the flange U which runs from the opening Z to the point

U^2 (Figs. 3 and 4) for about one-half of the circumference.

On that side of the rotary table directed toward the tool carrier, the clamping levers 5 are always closed as the flange U^2 lies lower than the way described by the antifriction rollers j^2 so that the springs f can press the bent ends of the levers j onto the cartridges.

After the cartridge cases have been placed 10 in the open bearings and the clamping levers have securely gripped the same they are successively transported beneath the tools carried by the tool carrier, the distance of the same from each other being determined by 15 the distance of five successive cartridge cases 1, 2, 3, 4, 5 from each other.

The first device which comes into operation 20 is the powder charging device attached to the powder receptacle N . The construction of 25 this device is similar to that described later on for the shot charging device and for the reamer or widener. The latter device serves to restore any cases, which may have become irregular, as to correct form before charging 30 same, and consists of a conical tubular spindle m attached to one of the sides of the plate D . Figs. 1 and 5, and fitting over the lower end of the powder feed tube n . By partially inserting this conical hollow spindle in the 35 mouth of the cartridge case, the mouth of the same is cylindrically enlarged during the charging of the case with powder.

The punch o is the second device which 40 comes into operation on the tool carrier D descending in order to force a felt wad r , cut out by means of a special device, into the cartridge case (2) already charged with powder. On the plate P are placed a series of wad carrier slides s radiating from the center of the 45 table, each provided with a ring shaped receptacle on the outer end to hold the wad, as shown in Fig. 2, where the slides are in section, and in Fig. 3, where they are shown in plan. The wads are fed to the slides by hand. 50 These slides are operated to present the wad carried thereby to the cartridge at the proper time and place, by a cam groove s^3 in the under face of the plate A^2 , the shape of which groove is shown in Fig. 3, into which extends 55 rollers s^2 projecting from the upper surface of the said slides. The groove is circular except at one point where it diverges outwardly and this causes the slides in the rotation of the plate P to follow the course of the groove 60 which thus at the proper time advances the slide to present the wad. The spring stop o^4 is clearly shown in Fig. 5, right hand side, so that as soon as a cartridge case during the 65 rotary movement of the table comes into the position 2 the tube s' on the slide s will be over the mouth of the cartridge case so that the punch o can drive the wad in the tube s' onto the powder charge. In the third position or above the cartridge 3 (Fig. 5) is the stationary tube w of the shot measurer. The construction of this device which corresponds

in all essential points with the powder measuring device is provided with a slide D' (Fig. 2) which in combination with the plate D is moved vertically between the plate W^2 and 70 the casing W' said slide having an inclined opening t and an adjustable piece D^2 in order to adjust the size of the shot measurer. In the uppermost position of the slide D' , the opening t comes into communication with the 75 inclined canal leading from the shot magazine W and receives the requisite charge of shot which on the descent of the parts will be filled into the cartridge (3) by means of the tube or channel w . As in some cases, especially with 80 large shot, a shot falls partly half into the opening t and would on the further movement of the slide be cut in two, I provide a piece of metal t' under spring action so arranged that the forward surface will as a rule be flush with the 85 surface of the slide and form a yielding edge. In consequence of an incline on the piece t' and the continued descent of the slide the superfluous shot will be forced into the space so formed but will by the next movement of 90 the slide at once fall into the opening t when the same during the upward stroke of the slide comes opposite to the said shot. A modification of this auxiliary device which can be omitted in the powder charging device (N, n) is represented in Fig. 7. In this case the lower surface t^2 of the charging canal is made to yield being held by the spring t^3 the bent end of which prevents the superfluous shot from falling out. As soon as the cartridge cases are as before described charged with powder and shot with intermediate felt wad the same come beneath a second punch o' (position 4) which acts similar to the punch o and which first cuts a cardboard wad out of a suitably transported band and then drives the same onto the shot charge. The ratchet device for transporting the cardboard band or strip and also a stamp o^2 , attached to the tool carrier, for numbering the wad is shown in Fig. 2 and partially in Fig. 3 but being well known to all versed in the art requires no further description. Both punch o and punch o' are as shown in Fig. 5 yielding attached in tubes to the reciprocating tool carrier so that the blow is not sudden but yielding and thus all undue strain on the parts avoided. In the fifth and last position (cartridge 5 Fig. 5) the new upsetting device or tool for bending over the edge of the cartridge case onto the upper wad comes into action and consists of a spindle v with upsetting tool u inserted in the head v' of the same. The spindle v has rotary motion and reciprocates vertically and is attached by the bearings V and V' to the frame and receives its rotary movement in any suitable manner from the mechanism. During the rotation of the rotary table the spindle is so far raised that the head will be above the way described by the cartridge cases. A spring stop o^4 connected to the tool carrier will, when the latter reaches the end of its

downward hub, drive the spindle or mandrel down so that the notches in the tool *u* in the head *v* will press on the upper edge of the cartridge case with increasing force. The pressure in conjunction with the rotary motion transmitted to the tool will upset or turn over the edge of the cartridge case so as to securely hold the cardboard wad above the charge of shot. The annular edge of the mouth of the head *v* prevents the edge of the cartridge case being turned outward.

In case the clamping by means of the spring *f* to the clamping device should not be sufficient during the upsetting of the upper edge 15 of the shell to firmly hold the cartridge, a leaf spring *f'* (Fig. 4) is arranged on the flange *U'* of the frame so that at the time mentioned the action of the roller *j* of the lever arms is increased.

20 As soon as the finished cartridge is moved with the rotary table *E* a distance equal to one tooth of the ratchet wheel, the same will fall through the opening *Z* as the same is on the one hand no longer supported by the flange 25 *U* and on the other hand is released from the grip of the clamping lever *f*, the roller *j* of which lies on the flange *U'*.

It will be seen from the above that the cartridge clamps will be at certain times in open 30 position ready for the insertion of fresh cartridge cases. The new felt wads are also inserted in the wad holders *s'* of the slide *s* from this side of the rotary table said slide being drawn inward.

35 At each rotation of the shaft *G* the machine will deliver a cartridge loaded in five operations which falls out at the opening *Z* into a collecting receptacle. Figs. 8 and 9 represent the modification for loading ball or military 40 cartridges all the essential points of the foregoing machine being employed. The empty metallic shells are fed from a tubular magazine *M* successively, by means of a wheel *L*, under suitable borings of the rotary table *E* the clamping device in this case being omitted. The cartridge shells are raised into the cartridge bearings by a connecting rod *k* when the borings align said rod being operated by a lever *l* and a tappet wheel (Fig. 8) the tappet only being shown. The borings in the rotary table *E* and the wheel *L* will correspond at each step of the ratchet wheel (Fig. 9). The powder feed is effected from the opposite side of the rotary table in precisely the same manner as described with reference to Figs. 1 and

55 7 while the bullets are driven in by a device similar to the wad feed, the radial slides *s* in this case forming the receivers *s'* for the bullets which when the same are above the cartridge cases 2 will be driven into the cartridge cases by the punch *o*. The devices for feeding the shot, upsetting the upper edge, &c.

are of course not necessary whereas an ejector is applied to the tool holder.

Having now particularly described the nature of my said invention and the manner in which the same is to be performed, I declare that what I claim, and wish to secure by Letters Patent, is—

1. A cartridge loading machine, consisting 70 of a rotating table carrying the cartridge cases, reservoirs for containing the material for the charging of the cartridges mounted on the frame of the machine, discharging tubes leading to the position of the shells to 75 be filled, a reciprocating tool carrier and vertically movable cut off slides operated by the tool carrier with inclined passages through the same, said slides being interposed between the reservoirs and the discharge tubes, 80 substantially as described.

2. In combination in a cartridge loading machine of a table carrying the cartridge cases, a reciprocating tool carrier, a discharge tube and a tubular reamer connected to the 85 tool carrier and encircling the end of the discharge tube, substantially as described.

3. A cartridge loading machine comprising a horizontal rotating table, a vertical reciprocating tool carrier, a horizontal crank shaft 90 *G*, a pitman *H* between the shaft and the tool carrier, an eccentric on said shaft *G*, a slide carrying a spring pawl to engage the toothed periphery of the table and a pitman rod connecting the shaft *G* and slide, substantially as described.

4. In combination with the rotating table, a series of recesses in its periphery adapted to receive the cases, spring arms carried by the table for clamping the cases within the recesses and a flange *U* supported by the base and arranged beneath the cartridges to support the same, substantially as described.

5. In combination with the table, a series of recesses in its periphery adapted to entirely receive the cases, pivoted spring arms located on the table and entirely within its periphery, rear extensions on said arms and flanges extending from the base in the path of said extensions, substantially as described.

6. In combination with the table, a reciprocating tool carrier, a punch *C* and a series of independently movable wad carriers on the table radiating from the center thereof, and means for reciprocating them laterally, substantially as described.

In witness whereof I have hereunto signed my name in the presence of two subscribing witnesses.

ARMIN TENNER.
